UNITED STATES PATENT OFFICE.

JAMES C. OLLARD, OF TACOMA, WASHINGTON, ASSIGNOR TO OLLARD TROLLEY WHEEL COMPANY, OF DOVER, DELAWARE.

COMPOUND TROLLEY-WHEEL.

1,240,358.

Specification of Letters Patent. Patented Sept. 18, 1917.

Application filed September 8, 1915. Serial No. 49,433.

To all whom it may concern:

Be it known that I, JAMES C. OLLARD, a citizen of the United States, residing at Tacoma, in the county of Pierce, State of Washington, have invented certain new and useful Improvements in Compound Trolley-Wheels, of which the following is a specification.

This invention relates to trolley wheels and has for its object to reduce the cost of such wheels and to provide a bearing surface of hardened metal.

I attain these and other objects by the devices and arrangements illustrated in the accompanying drawings, in which—

Figure 1 is a side elevation of my improved trolley-wheel; Fig. 2 is a cross-section of one of the arms or spokes thereof; Fig. 3 is a section on the line 3—3 in Fig. 1; Fig. 4 is a side elevation, partly in section, of the central portion thereof; and Fig. 5 is a similar view of a part of the outer or rim portion thereof, the central or hub portion having been removed therefrom.

Similar numerals of reference refer to similar parts throughout the several views.

Trolley wheels have heretofore been made in one casting, usually of brass or one of the various bronze compounds, and these metals are very desirable for the outer or rim parts of such wheels, but all these compounds are expensive and the castings have to be made quite thick to give the wheel the strength and wearing qualities required in practical operation. Further, it is often necessary to provide a special hardened bushing in the center of such wheel to take the wear of the bearing pin. In order to overcome these difficulties I have invented the following described compound trolley wheel.

I first provide a central or hub portion which may be made of cast iron, cast steel, or other cheap metal, said hub portion being provided with a suitable central boss through which the bearing hole passes, the walls of said hole being suitably hardened to resist the wear thereon. This boss has a flange or web extending from its outer surface, or has a series of arms thus extending, as shown, said arms being used for the larger size of wheels, while the web is used for smaller wheels. This central hub

portion is then laid in the mold for the outer portion and the said bronze compound is 55 poured in the mold in a molten state and is thus cast on to the said web or arms. Suitable integral lugs or keys are provided around the inner surface of the annular ring of bronze thus cast, said lugs being 60 adapted to engage the inner portion to hold said parts from circumferential motion relative to each other.

In the drawings the iron hub is provided with a boss 1 having a bearing hole 2 therethrough, the walls thereof being chilled or otherwise hardened to resist the wear of the bearing. A plurality of arms or spokes 3 extend from the boss 1. Each arm is shaped on its outer edge to conform to the 70 shape of the bronze wheel, as shown in Fig. 3. The bronze wheel 4 is cast outside of the hub arms 3 and is of uniform section at all points, being provided however with small lugs or keys 5 on each side of the 75 said arms 3. The wheel may be of any approved section as shown and has a thick wearing body 6 immediately adjacent said arms 3.

Thus it will be seen that the wheel thus 80 formed will consist of a less expensive metal than usual and will therefore be cheaper; that its life will depend on the thickness of the wearing body 6 and not on the bearing; that when the rim has worn through, the 85 hub may again be used by casting it into a new rim; and that this form of trolley wheel has many practical commercial advantages over a similar wheel made of one metal. 90

Having described my invention, what I claim is:

A trolley wheel having a central hub of iron with arms extending outward therefrom; an annular rim of good conductive 95 metal surrounding said hub and cast to said arms, said rim having a V-shaped groove in its outer face whereby flanges are formed whereby every part of the wheel which may come in contact with the trolley 100 wire is formed of said good conductive metal, said rim extending from arm to arm around the hub and having lugs formed on its inner face adjacent to and in contact with said arms. 100

JAMES C. OLLARD.
